(57) CLAIM

The ornamental design for a wheeled base assembly for a textile luggage case, as shown and described.

DESCRIPTION

FIG. 1 is a front perspective view of the wheeled base assembly for a textile luggage case embodying our new design.

FIG. 2 is a rear perspective view thereof.

FIG. 3 is a front elevational view thereof.

FIG. 4 is a rear elevational view thereof.

FIG. 5 is a right side view thereof; and,

FIG. 6 is a left side view thereof.
